(57) **CLAIM**

The ornamental design for a connector as shown and described.

DESCRIPTION

FIG. 1 is a perspective view of a connector showing the new design;

FIG. 2 is a front view thereof;

FIG. 3 is a rear view thereof based on FIG. 2;

FIG. 4 is a left-side view thereof based on FIG. 2;

FIG. 5 is a right-side view thereof based on FIG. 2;

FIG. 6 is a top plan view thereof based on FIG. 2;

FIG. 7 is a bottom view thereof based on FIG. 2; and,

FIG. 8 is a bottom perspective view thereof based on FIG. 2.

The portions of the article illustrated using broken lines form no part of the claimed design for the connector.
